UNITED STATES PATENT OFFICE.

WILLIAM T. HOFMANN, OF CHICAGO, ILLINOIS, ASSIGNOR TO BECKMAN-DAWSON ROOFING COMPANY, OF CHICAGO, ILLINOIS, A CORPORATION OF ILLINOIS.

LOOPING SYSTEM.

Application filed February 2, 1921. Serial No. 441,940.

To all whom it may concern:

Be it known that I, WILLIAM T. HOFMANN, a citizen of the United States, residing in Chicago, county of Cook, and State of Illinois, have invented certain new and useful Improvements in Looping Systems, of which the following is a specification.

This invention relates to improvements in looping systems and refers more particularly to drying or cooling apparatus used in connection with paper or roofing machinery.

The important objects of the invention consist in the use of a combination of three friction drawn rolls for feeding out the paper or roofing sheet to be looped over an endless travelling chain, and, secondly, the positioning of the three draw rolls in a manner so that the sheet is not subjected to undue strain as it is drawn into the looping apparatus, and, thirdly, the use of a flanged guide roll for positively directing the course of the sheet subsequent to its travel through the cooling apparatus.

Heretofore, pressure rolls have been employed in feeding out the paper to the looping apparatus, but constant difficulty has been experienced with these pressure rolls in that the sheet is unduly squeezed and its texture weakened thereby causing numerous shut-downs and delays for this reason. Similar inconveniences have been experienced with the draw rolls at the discharge end of the apparatus and for want of a proper guiding means the course of the sheet has not been properly directed from the looping apparatus to the saturator, coater, cutter or printing devices connected therewith.

In the drawings—

Fig. 1 is a side elevation of the looping apparatus with parts omitted.

Fig. 2 is a plan view of the apparatus shown in Fig. 1.

Referring to the drawings—the details of the drive have been purposely omitted to avoid complication of the apparatus more pertinent to the invention. Generally, the purpose of a looping system of this type is to maintain the roofing felt or sheet or paper sheet, whichever the case may be, in a series of loops for the purpose of drying or cooling the paper or hot coating substance in a case of prepared roofing.

Describing briefly the drive,—power from any suitable source is transmitted to

the shaft 1 through gears 2 fixedly mounted to the shaft. The shaft is mounted in a triple bearing arrangement 3 supporting also the shafts 4 and 5 on which are mounted the feed-in rolls 4^a and 5^a respectively. Meshing gears 6 also mounted upon these shafts transmit power from the shaft 1 and cause the three rolls 1^a, 4^a and 5^a mounted on the shafts 1, 4 and 5, respectively, to rotate in unison. The machine proper comprises a frame 7 supporting sprockets 8 over which runs the endless chain 9 having rolls 10 interposed between a bearing and the flexible side portions of said endless chain. This endless chain 9 over which the sheet is looped is driven in timed relation with the shaft 1 in the following manner: A sprocket 11 mounted on the shaft 1 drives the larger sprocket 12 mounted upon the shaft 13 by means of a chain 14. A sprocket 15 also mounted upon the shaft 13 transmits this rotary movement to a similar but somewhat larger sprocket 16 mounted upon the shaft 17 through the chain 18. The shaft 17 also carries the sprocket over which the endless chain 9 travels and in this manner drives the looped sheets which are carried by the endless chain 9 at the proper rate. The feed of the sheet to the apparatus consists in threading the sheet over the top of the roll 5^a, under the roll 4^a and over the top of the final feed-in roll 1^a. An idler 19 keeps the sheet at all times in close contact with the upper or final-feed-in roll 1^a. Subsequent to passing over the roll 1^a, the sheet travels down over one of the small rollers positioned between the two sides of the endless chain 9 and is for an instant held in contact with each of the succeeding rolls of the looping chain as it moves along, by means of the idler 20. The speed of travel over the feed-in rolls is sufficient to produce loops as shown at 21 before the endless looping chain has proceeded to a position where the idler 20 will direct the sheet over the next succeeding roll.

In this way, there are a series of loops at all times in the apparatus which move slowly along until the loops reach a position at the end of the machine where the sheet or felted material is drawn off and fed to a saturator, cooler, cutter or other type of machine to which it travels as a succeeding stage in its manufacture.

It has been the usual practice to draw off

the material from the cooling or looping system by causing it to pass over an idler roll. The disadvantages of uneven feed to the next unit caused by the use of an idler have been obviated in the present device by positioning two rolls 22 and 23 in a manner so that the sheet coming from the looping system may be threaded on to the roll 23, thence between the two rolls and over the top of the roll 22 from which it depends in a loop and from this loop is directed through the guide roll 24 on to whatever machine may be used as the next succeeding step. The guide roll 24 has a wide flange 25 at both ends between which the sheet travels and which serve to positively direct the sheet so that it will be fed properly to the next adjoining machine. The draw rolls 22 and 23 are driven from the shaft 26 by means of the bevel gears 27, sprocket 28, mounted upon a transverse shaft 29, and chain 30 and sprocket 31 mounted upon the shaft 32 which also supports the roll 23.

It is obvious that the three feed-in rolls 25 may be positioned in various ways at the same time effecting as efficient a feeding means as the positioning shown in Fig. 1. It is not my purpose to restrict the invention to the positioning of these rolls, but only to disclose the use of feed-in rolls that do not rely upon the gripping pressure between said rolls to feed the sheet to the apparatus. Similarly, the draw-off rolls may be positioned in numerous ways to draw the sheet 35 from the final loop, but here again I desire only to disclose a manner of positioning the rolls whereby the sheet is drawn out of the looping system by pressure due to the contacting of the draw-off rolls. By positioning the feed and draw-off rolls in the manner described I have obviated to a great extent the difficulties which are constantly encountered with the use of pressure feed and idler draw-off rolls in looping systems.

45 I claim as my invention:

1. In a looping apparatus, the combination with an endless means for supporting a plurality of loops of flexible materials, of feed in rolls adjacent the inlet end of the endless means through which the flexible material is threaded and drawn into the looping apparatus, the arrangement of these rolls being such that the material is drawn into the

looping apparatus without being subjected to the squeezing effect of pressure rolls. 55

2. In a looping apparatus, the combination with an endless means for supporting a plurality of loops of flexible materials, of feed in rolls adjacent the inlet end of the endless means through which the flexible material is threaded and drawn into the looping apparatus, the arrangement of these rolls being such that the material is drawn into the looping apparatus without being subjected to the squeezing effect of pressure rolls, gripping drawoff rolls adapted to withdraw the flexible material from the last loop on the endless means, said gripping drawoff rolls forming an additional loop beyond the endless means. 60 65

3. In a looping apparatus, the combination with an endless means for supporting a plurality of loops of flexible materials, of feed in rolls adjacent the inlet end of the endless means through which the flexible material is threaded and drawn into the looping apparatus, the arrangement of these rolls being such that the material is drawn into the looping apparatus without being subjected to the squeezing effect of pressure rolls, gripping drawoff rolls adapted to withdraw the flexible material from the last loop on the endless means, said gripping drawoff rolls forming an additional loop beyond the endless means, and a flanged 70 75 guide roll for positively directing the subsequent course of the flexible sheet in its travel to the next succeeding step of operation. 80

4. In a looping apparatus, the combination with endless chains having spaced apart rolls positioned therebetween for supporting a plurality of loops of a sheet of flexible material, of feed in rolls adjacent the inlet to the endless chain functioning to introduce the sheet without subjecting same to pressure, pressure drawoff rolls adjacent the discharge from the endless chain for removing the sheet of flexible material, said pressure drawoff rolls forming an additional loop 85 exterior of the endless chain, and a flanged guide roller receiving the sheet of flexible material from the last mentioned loop and accurately directing its course as it is fed to the next succeeding step of operation. 100

WILLIAM T. HOFMANN.
